UNITED STATES PATENT OFFICE.

MILLARD L. DUNHAM, OF NEW YORK, N. Y., ASSIGNOR OF ONE-FOURTH TO LOUIS DE F. MUNGER, OF NEW YORK, N. Y.

PISTON-RING.

1,241,837.

Specification of Letters Patent.

Patented Oct. 2, 1917.

Application filed April 18, 1916. Serial No. 91,857.

To all whom it may concern:

Be it known that I, MILLARD L. DUNHAM, a citizen of the United States, and resident of the borough of Manhattan, in the city, county, and State of New York, have invented certain new and useful Improvements in Piston-Rings, of which the following is a specification.

This invention relates to piston rings, and it consists in certain characteristic features in rings produced from circular blanks which are normally oversize, whereby when said rings are contracted in use they are of true cylindrical contour.

Piston rings are usually made from cast iron, and rely for their outward tension, whereby gas tight relationship with the cylinder wall is provided, upon the inherent elasticity of the material from which cast, in the restorative effort toward resumption of their original contour; after the inward compression to which they must be subjected in order to introduce the rings, upon a piston, within the cylinder. Thus the rings are usually cast of a diameter greater than the inside diameter of the cylinder with which they are to be used, and are split at one point, by the removal of a portion of the ring material, leaving two opposed ends, to provide space for the aforesaid inward compression; the space being of such extent only that when abridged by the inward compression for service, the opposed ends will have spaced relationship just sufficient to serve the purposes of heat expansion and contraction in use.

Under this ordinary method of piston ring manufacture the true circular form becomes distorted when the ring is contracted to fit within the cylinder; the distortion consisting in portions of the ring, near its ends, lagging inwardly, leaving clearances between the outer peripheral surface of said portions—over certain arcs—and the opposed portions of the cylinder wall. These clearances permit sufficient leakage to affect the cylinder compression.

Various means have been sought to rectify this deficiency in piston rings, and my present invention is directed to a circular ring, produced in the ordinary way, and treated in a novel, simple and efficacious manner, whereby it is caused to have a true

circular contour after it has been contracted to fit within a cylinder. 55

This treatment, in brief, consists in first cutting a piece out of a cast ring, in the usual manner, leaving opposed, separated ends; and then in spreading the mass of the ring material at its outer peripheral surface, in portions thereof adjacent to each of its opposed ends; to thereby give those portions, equally, an inherent, inward inclination; which constitutes, in the free state of the ring, a distortion thereof from a true circle; but which, in the contracted state of the ring, for service, gives it an absolutely true circular contour; whereby the clearances before referred to as existing between the ring portions, near their ends, and the cylinder wall, are entirely filled. 60 65 70

Spreading the mass of the ring material, on the outer surface thereof, in its portions toward the ring ends, has the effect of drawing the end portions of the ring inwardly, 75 to give them equally a distorted contour, wherein the ends aforesaid are inclined inwardly, and said end portions caused to describe a segment of a circle whose diameter is slightly less than the diameter of the untreated portion of the ring in its free state. 80

This may be accomplished by punching indentations in the outer peripheral surface of the ring, over longitudinal portions thereof including the ring ends and sections anterior thereto; the circumferential ring portions, thus defined, comprising the arcs referred to in which leakage clearances exist under the present construction of piston rings. 90

The mass spreading, as by punching of indentations aforesaid, has the effect of drawing inwardly the ring end portions, to thus slightly distort the ring in its free state; but causing it to have a true cylindrical contour when contracted in service. The stated result is achieved without detraction from the inherent elasticity of the ring material; the ring, after treatment, functioning as before; with the exception that, on account of its treatment, it is enabled to fit snugly within a cylinder, without leaving any clearance spaces. 95 100

The reason for the above noted change in the contour of the ring is because of the mass displacement referred to; which, oper-

ating with the heel of the ring as a fulcrum, as stated draws inwardly the end portions; whereby the ring, when contracted, assumes a true cylindrical form.

5 Other features and advantages of my said invention will hereinafter appear.

In the drawing:

Figure 1 is a plan view of a circular ring from which a section has been removed to 10 permit contraction.

Fig. 2 is an edge view thereof, showing the method of forming indentations therein to spread the mass of the material.

Fig. 3 is a plan view, showing the effect 15 of the mass spreading in changing the ring contour at one side of the spacing.

Fig. 4 is a similar view, showing the ring as treated in Fig. 3, to fit within a cylinder.

Fig. 5 is an enlarged detail view, showing 20 the ring as treated at both sides of the spacing and contracted to fit within a cylinder, and.

Fig. 6 is an edge view of the ring shown in Fig. 5.

25 In producing my improved piston rings from circular castings of larger diameter, I remove a section from a circular ring, as 1, leaving the opposed ends 2, 3, spaced apart sufficiently to allow the inherent elasticity 30 of the ring material, when the ring is fitted within a cylinder, to exert the desired degree of outward tension. The fault in this general form of ring construction, as now practised, is that while the diameter of the 35 ring, in a line drawn through its joint and heel, will remain practically unchanged when contracted, the side portions of the ring, near the joint, will then sag inwardly, when contracted, leaving at those points 40 leakage spaces between the ring and cylinder. This defect is remedied by me by distorting the ring from its circular condition shown in Fig. 1, through a certain treatment which results in causing the ring ends 2, 3, 45 and portions adjacent thereto to incline inwardly, having the effect, when the ring is contracted, to bring its ends together, of then causing the ring to assume a true circular form.

50 Fig. 2 illustrates the character of the treatment applied, which is that of punching indentations, as 4, in the outer peripheral surface of the ring, along restricted por-

tions thereof lying between the ring ends and a medial line drawn across the ring, between its joint and heel.

55 Said indentations are produced by a tool, as 5, and serve to slightly spread the mass of the ring material at those portions, which has the effect of giving the ring a permanent 60 distortion in its free state, as stated, which distortion enables the ring to assume an absolutely true circular form when contracted.

Reference to Fig. 3 will show one side only 65 of the ring as treated, the treated side 5^a, in the free state of the ring being distorted, while the opposite side 6 remains of circular form. In further illustration of the effect thus obtained, I have shown, in Fig. 4, the partly treated ring of Fig. 3 as contracted 70 and placed within a cylinder 7. It will there be seen that the treated portion of the ring, as contracted, fits perfectly within the cylinder 7, the opposite, untreated side 6 of the ring appearing as distorted in the contracted 75 state, whereby a clearance is seen to exist between said portion 6 and the cylinder wall. The efficacy of this treatment, as applied to both portions 5^a and 6 of the ring, is clearly shown in Fig. 5, where the ring is seen to 80 fit closely within the cylinder.

85 Attention is directed to my co-pending application, Serial No. 91856, filed April 18, 1916, for a method of producing improved piston rings, which is the subject of this application.

Variations may be resorted to within the spirit and scope of my invention.

I claim:

A piston ring consisting of a separated, 90 circular metal ring, whose normal diameter exceeds the inside diameter of the cylinder with which used, said ring having the mass of its outer peripheral material displaced at the end portions of the ring, giving said end 95 portions an inward inclination, whereby the ring, when contracted in use, is of true circular form.

Signed at the borough of Manhattan in the city, county and State of New York this 100 14th day of April A. D. 1916.

MILLARD L. DUNHAM.
